WHEEL FOR A JUVENILE VEHICLE

Viktor Schreckengost, Cleveland Heights, Ohio, assignor to The Murray Ohio Manufacturing Co., Nashville, Tenn.

Filed Sept. 22, 1971, Ser. No. 182,927

Term of patent 14 years

Int. Cl. D21—01

U.S. Cl. D34—15 AJ

Fig. 2

FIG. 1 is a side elevational view of a wheel for a juvenile vehicle showing my new design, the side opposite being identical except that the valve is eliminated;

FIG. 2 is a top plan view thereof.

I claim:

The ornamental design for a wheel for a juvenile vehicle, substantially as shown.
